OR D 5,862

UNITED STATES PATENT OFFICE.

EMILE DEMOUSSY, OF PARIS, FRANCE, ASSIGNOR TO JOSEPH WILD & CO.,
OF NEW YORK, N. Y.

DESIGN FOR A CARPET-PATTERN.

Specification forming part of Design No. 5,862, dated May 21, 1872.

Specification describing a new and original Design for a Carpet, invented by EMILE DEMOUSSY, of Paris, in the Department of the Seine, France.

The accompanying photographic illustration fully represents my new design.

This invention relates to an ornamental design for carpets and other fabrics; and consists in the new configuration of the two main figures used in said carpet.

One of these figures is of circular or nearly circular form, with four projections at its cir-

cumference, each projection being similar in shape to a letter **M**. The other figure is rectangular, with concave sides. The ornamentation of these figures is variable, though fully shown.

I claim as my invention—

The design for a carpet, as shown.

E. DEMOUSSY.
